UNITED STATES PATENT OFFICE.

WILLIAM SCHROEDER, OF KENDALLVILLE, INDIANA.

DESIGN FOR A BROOM-HOLDER.

SPECIFICATION forming part of Design No. 19,517, dated December 17, 1889.

Application filed November 13, 1889. Serial No. 330,216. Term of patent 14 years.

To all whom it may concern.

Be it known that I, WILLIAM SCHROEDER, a citizen of the United States, residing at Kendallville, in the county of Noble and State 5 of Indiana, have invented a new and useful Design for a Broom-Holder, of which the following is a specification.

The invention relates to a new and original design for broom-holders.

10 In the drawings, Figure 1 is a perspective view of a broom-holder showing my design. Fig. 2 is a plan view.

The leading feature of my design consists in the wire frame for holding the broom, which 15 frame is provided with a large loop at its upper end and a small one at its lower end, and it has irregularly-bent side wires connecting the loops.

A designates the back of the broom-holder, 20 which is approximately the shape of a shield and has a curved and ornamental outline.

B designates the wire broom-holding frame, which has at its upper end a large transverse loop a , and has at its lower end a small circular transversely-arranged loop a' . The 25 loops are open and are connected by irregularly-curved side wires a^2 .

What I claim is—

The design for a broom-holder herein shown and described, the same comprising the back 30 A and the wire broom-holding frame having at its upper end the large loop a and at its lower end the small circular loop a' , and provided with irregularly-curved side wires a^2 , connecting the loop, substantially as set forth. 35

In testimony that I claim the foregoing as my own I have hereto affixed my signature in presence of two witnesses.

WILLIAM SCHROEDER.
